J. W. KENNEDY.

RAILWAY SIGNALING APPARATUS.

APPLICATION FILED SEPT. 8, 1921.

1,421,252.

Patented June 27, 1922.

UNITED STATES PATENT OFFICE.

JAMES W. KENNEDY, OF CANTON, OHIO, ASSIGNOR OF ONE-FOURTH TO GEORGE S. HAGGART AND ONE-FOURTH TO HARRY C. CONRAD, BOTH OF CANTON, OHIO.

RAILWAY SIGNALING APPARATUS.

1,421,252.

Specification of Letters Patent. Patented June 27, 1922.

Application filed September 8, 1921. Serial No. 499,296.

To all whom it may concern:

Be it known that I, JAMES W. KENNEDY, a citizen of the United States, residing at Canton, in the county of Stark and State 5 of Ohio, have invented certain new and useful Improvements in Railway Signaling Apparatus; and I do here declare the following to be a full, clear, and exact description of the invention, such as will enable 10 others skilled in the art to which it appertains to make and use the same.

My invention relates to signaling apparatus for use on railroads, and consists of certain novel and useful improvements in the 15 same, which will be fully disclosed in the specification following, reference being had to the accompanying drawings, in which my invention is illustrated, and being more particularly pointed out in the appended claims.

20 My present invention may be said to be an improvement in the signaling apparatus, shown and described in my pending application filed July 13, 1921, in which I disclose an apparatus, operated by a device 25 located upon the roof of a moving vehicle, by contacting with depending arms, overhanging the track and pivotally mounted on upright supports.

The object of my present invention is to 30 do away with the overhanging arms and devices mounted on the roof of a moving vehicle, and to this end I provide operating means for my signaling apparatus, which are located close to the ground, and which 35 are adapted to be moved to a desired position, by a shoe secured to the underside of a moving vehicle, otherwise my signaling apparatus operates in a manner identical with that set forth in my aforementioned 40 pending application.

In the drawings,—

Figure 1 represents a railroad track equipped with my improved apparatus, and operable either by a device located on the 45 roof of a moving vehicle as in my former application, or by a shoe placed upon the underside of said vehicle, as in my present application;

Fig. 2 is a side view of the pilot and forward portion of a moving vehicle, provided with a shoe upon its underside.

Similar numerals indicate identical parts throughout.

1, 2, 3, 4 represent the usual rails, secured to cross ties of a railroad in the ordinary manner, and it is obvious that these ties may be of wood or concrete, as desired.

Secured to a cross-tie as for example 5, or otherwise held firmly in place are bearings 6 and 7 in which there is rotatably 60 mounted a rod 8 having an upwardly projecting pin 9 adapted to engage a slot 10 in the sleeve 11, rigidly secured to the longitudinally extending rod 12 slidably mounted in suitable supports 13 secured to 65 the ties.

14 is a rod pivotally mounted at one end, as at 15, upon one of the cross ties and being provided at its other end with a downwardly projecting hook portion, adapted 70 to engage a pin 16, projecting from the rod 8. This hook portion may be bifurcated to facilitate its engagement with the pin, the latter resting in the fork. The longitudinal rod 12 is provided at one end with 75 a sleeve 17, having a slot adapted to be engaged by a pin or loop secured to the transverse rod 18, rotatably mounted in bearings 19 suitably secured in place.

The rod 18, is provided with projecting 80 pins 21 and 22 for a purpose hereinafter described, and at one end thereof, there is rigidly secured a bell crank lever 23, the outer end of which is pivotally secured to a vertically disposed arm 24 for operating the 85 signaling device, as will be later described.

50 is a rod similar to the rod 14, pivotally mounted at one end as at 51 and being provided at its other end with a downwardly extending bifurcated hook portion 52, which 90 engages the pin 21, of the transverse rod 18.

Referring now to Fig. 2, 25 is a shoe preferably constructed of spring metal, and rigidly secured to the underside of a moving vehicle, and a short distance from the inner 95 side of the wheel 26. The shoe 25 is bent downwardly and longitudinally and is provided with an upwardly projecting pin 27, surrounded by a coiled spring 28 which abuts against the underside of the vehicle, 100 and if desired a socket 30 may be provided in the vehicle into which the pin projects, and loosely operates.

The shoe 25 is bent downwardly a sufficient distance to come in contact with the 105 rod 14 for a purpose hereinafter disclosed.

31 represents a longitudinally extending rod pivotally mounted at 32 and provided with a bifurcated portion 33 to engage the pin 22, of the rod 18, the opposite end of said 110

rod being preferably bent downwardly as shown.

The operation of the apparatus described is apparent. Assuming that no signal is set, a moving vehicle, provided on its underside with my improved shoe, entering the section of track where the signaling devices are located, causes the shoe to come in contact with the pivotally mounted rod 14, and 5 depress the hooked portion, thereby rotating the transverse rod 8, which engaging the sleeve 11 with the pin 9 moves the longitudinally extending rod 12, thereby rotating the transverse rod 18, and moving the vertical rod 24 to set the signal by means of the wires 40 and 41 and the other auxiliary device 10 fully described in my aforementioned co-pending application, and not necessary to describe in detail here.

20 As the vehicle proceeds, the shoe comes in contact with the rod 50, and sliding upon the same depresses the pin 21 and rotates the rod 18, rocks the arm 23, raises the arm 24 and sets the signal for safety.

25 It is obvious that as the moving vehicle passes over the rod 50, the pin 22 will be depressed, and the rear end of the rod 31 will be raised.

30 Under these circumstances, it may be desirable to back the vehicle and in backing to again set the danger signal. This is accomplished by placing a second shoe, similar in all respects to that already described, on the underside of the vehicle and in such position as to contact with the rod 31, when backing, thereby depressing the rear portion of said rod 31 and rotating the rod 18, thus again setting the signaling apparatus to indicate danger.

40 The backing shoe is set over nearer the center of the track. When the first shoe passes over the rod 14 and thereby rotates the rod 18, the hook 52 is up and the rod 31 is down. When said shoe comes to the hook 45 52, it depresses it, and rod 31 is raised, but in the meantime the second shoe has passed over and escaped the rod 31, and as the other one is down, does not actuate the device.

50 In backing, the reverse takes place, and as the second shoe reaches the raised portion of rod 31, it depresses the same and re-sets the danger signal.

55 One of the advantages of my construction is that the shoes are so located and constructed, that if they come in contact with any obstacle such as track crossings, switch frogs, boards of highway crossings, or any object projecting above the top of a rail, said 60 shoes will yield to avoid breakage, and immediately and automatically resume an operable position.

65 While I have described my improved apparatus in detail it is obvious that such detail may be changed, as desired, without de-

parting from the spirit of my invention, so long as such changes come within the scope of the claims.

What I claim and desire to secure by Letters Patent is:—

70 1. Apparatus for operating a permanently located semaphore placed at one side of a rail road track, comprising a longitudinally extending slidably mounted rod, a plurality of transverse rotatably mounted rods, connected to the longitudinal rod, an operating rod for rotating one of the transverse rods and means mounted on a moving vehicle for actuating the operating rod, and the rods connected therewith.

75 2. Apparatus for operating a permanently located semaphore, comprising a longitudinally extending slidably mounted rod, a transverse rotatably mounted rod operably connected with the semaphore and with the longitudinally mounted rod, an operating rod pivotally mounted at one end and having its other end in engagement with a part projecting from the transverse rotatable rod, a second operating rod pivotally mounted at a point approximately midway of its length, means secured to a moving vehicle for actuating the operating rod when the vehicle is moving forwardly, and other means for actuating the second operating arm when the vehicle is moving rearwardly.

80 3. Apparatus for operating a signaling device, comprising a longitudinally extending slidably mounted rod, a transverse rotatably mounted rod, operably connected with the signaling device and with the longitudinally extending rod, an operating rod pivotally mounted at one end and having its other end in engagement with a part projecting from the transverse rotatable rod, a second operating rod pivotally mounted at a point between its extremities, means secured to a moving vehicle for actuating the operating rod in the forward movement of the vehicle and means for actuating the second operating rod, in the rearward movement of the vehicle, the point of pivoting of the second operating rod, being such that the first named means will clear its operating rod in a rearward movement and the second means will rotate the transverse rod and re-set the signal for danger.

85 4. Apparatus for operating a signaling device, comprising a longitudinally extending rod, slidably mounted in suitable bearings, transverse rods rotatably mounted in bearings, means for connecting the longitudinal and transverse rods, an operating rod for rotating one of the transverse rods and means for actuating the operating rod, said means 90 consisting of a shoe secured to the underside of a moving vehicle, said shoe being made of resilient material, and being adapted to contact with the pivotally mounted actuating rod.

5. A shoe for actuating operating apparatus for a signaling device, said shoe comprising a strip of resilient material rigidly secured at one end to the underside of a moving vehicle, and having its free end bent downwardly and rearwardly, an upwardly extending pin secured to the free end, said pin being adapted to enter an opening in the underside of the vehicle and a spring interposed between the free end of the shoe and the vehicle.

6. Apparatus for operating a signaling device, comprising a longitudinally extending slidably mounted rod, a transverse rotatably mounted rod operably connected with the signaling device and with the longitudinal rod, an operating rod pivotally mounted at one end and having its other end in engagement with a part projecting from the transverse rotatable rod, a second operating rod pivotally mounted at a point approximately midway of its length, and two shoes secured to the underside of a moving vehicle, one of said shoes being adapted to actuate the operating rod when moving downwardly and

the other to actuate the second operating arm when moving rearwardly.

7. Apparatus for operating a signaling device, comprising a longitudinally extending slidably mounted rod, a transverse rotatably mounted rod operably connected with the signaling device and with the longitudinally extending rod, an operating rod pivotally mounted at one end and having its other end in engagement with a part projecting from the transverse rotatable rod, a second operating rod pivotally mounted at a point between the extremities, and two shoes secured to the underside of a moving vehicle, one of said shoes being adapted to actuate the operating rod in its forward movement, and the other to actuate the second operating rod in its rearward movement, the point of pivoting of the second operating rod being such that the first-named shoe will clear its operating rod in a rearward movement, and the second shoe will rotate the transverse rod and reset the signal for danger.

In testimony whereof I affix my signature.
JAMES W. KENNEDY.
